UNITED STATES PATENT OFFICE

JAMES M. SHOEMAKER, OF WASHINGTON, DISTRICT OF COLUMBIA

INTERNAL COMBUSTION ENGINE

Application filed June 8, 1929. Serial No. 369,459.

This invention relates to internal combustion engines, and more particularly to means adapted to facilitate the starting of such engines.

5 The starting of high powered internal combustion engines, and particularly aeroplane engines, in cold weather presents many difficulties, and this is primarily due to improper volatilization of the fuel. In order to facilitate the starting of a cold engine it is common practice to greatly enrich the fuel mixture, but this results in excessive wear of cylinders, pistons, and piston rings, increases fuel consumption, dilutes the lubricating oil, etc.

10 One of the objects of the present invention is to provide novel means for facilitating the starting of engines, and particularly the starting of engines at low temperatures.

Another object is to provide novel means 20 whereby a cold engine may be supplied with a properly volatilized charge of fuel and air during the cranking operation.

A further object is to provide means of the above character which are adapted to be actuated prior to the starting operation and which do not depend on heat generated by the operation of the engine for their efficiency.

Another object is to provide novel means for heating the intake manifold of an internal 30 combustion engine, prior to the starting of said engine, whereby the engine, when cold, will be supplied with a highly volatilized combustible charge.

A still further object is to provide novel means of the above character in combination with indicating means whereby the operator may accurately determine when it is desirable to crank the engine to start it.

Another object includes the provision of 40 novel means of the above character which are simple in construction and are adapted to be easily applied to engines now in use. The above and other objects will appear more fully hereinafter.

45 Several embodiments of the present invention are illustrated, somewhat diagrammatically, in the accompanying drawings, where-in like reference characters refer to like parts throughout the several views, but it is to be expressly understood that the drawings are

for purposes of illustration only, and are not designed as a definition of the limits of the invention, reference being had for this purpose to the appended claims.

In the drawings:

Fig. 1 is a diagrammatic view illustrating one embodiment of the present invention in combination with the fuel supply system of an aeroplane engine;

Fig. 2 is a side elevation in section of another embodiment of the present invention;

Fig. 3 is a sectional view taken on the line 3—3 of Fig. 2;

Fig. 4 is a sectional side view of another structure embodying the present invention;

Fig. 5 is a section taken on the line 5—5 of Fig. 4;

Fig. 6 is a diagrammatic view illustrating an electrical circuit, which is preferably employed in accordance with the present invention; and

Figs. 7 to 9 inclusive, are sectional side views of other structures embodying the present invention.

One form of the present invention is shown in Fig. 1 in combination with a fuel supply system for an aeroplane engine, which system includes a main fuel tank 10, a gravity tank 11, and a carburetor 13 connected to an intake manifold 14 which leads to the engine cylinders (not shown). As is well understood by those skilled in the art, fuel is supplied to carburetor 13 from either the main fuel tank 10 or gravity tank 11.

Flow of fuel from the gravity tank is through a pipe 15 controlled by a suitable valve 16. When the main tank is employed, fuel is drawn through pipe 17 and strainer 18 by means of an engine driven pump 19, which is provided with a suitable relief valve.

When the pump operates at a speed sufficient to develop a pressure in the fuel line to the carburetor in excess of that set on the relief valve, the latter opens and the excess fuel is pumped through line 20 and pipe 15 into the gravity tank, the valve 16 being closed.

If pump 19 is inoperative, either by reason of the engine being stopped or through failure of the parts, fuel may be supplied to the carburetor through line 15 by opening valve 16, or from the main tank by

actuating a hand pump 21. When the latter is actuated the fuel passes through a by-pass in pump 19 to the carburetor. Since the above parts are of usual and well known construction and constitute no part per se of the present invention, a detailed description of the construction and operation thereof is unnecessary.

- 5 In order that the charge drawn through the intake into the cylinders during the starting operation may be sufficiently volatilized to insure prompt starting even in the coldest weather, novel means are provided for heating the intake pipe 14 prior to the cranking 10 of the engine. To this end a jacket 22 is provided for the intermediate portion of the intake pipe 14. The diameter of the jacket is such that an annular heating chamber 22^a is formed around the intake pipe, which chamber is provided with an air inlet 23 and an outlet 24 for burned gases, which latter may, if desired, be led around or through the oil tank 12. A pipe 25, which, in the form shown, is connected to the fuel system intermediate 15 carburetor 13 and pipe 15 provides means for conducting fuel into the chamber 22^a. Preferably a manually operable plunger pump 26 is interposed in pipe 25, together with a manually operable valve 27, whereby 20 liquid fuel may be forced through a nozzle 28 into the preheater chamber. If desired, a pressure gauge 29 may be connected to pipe 25 at a suitable point, and a two-way valve 30 may also be fitted in said pipe 25 to permit 25 fuel to be forced by pump 26, when desired, to a priming outlet 31 for the engine.
- Positioned in the lower portion of the preheater chamber and insulated therefrom in any suitable manner is a heating coil 32 adapted to be connected by means of a switch 33 to a suitable source of power, such as a battery 34. The battery is also connected by suitable leads to an indicating device, such as an ammeter 35, and to a suitable thermostat 40 36 which surrounds intake pipe 14, closely adjacent jacket 22. If considered desirable, screens 37 and 38 may be placed in the exhaust and intake pipes 24 and 23 respectively, to minimize fire hazards.
- 45 In operation switch 33 is closed to supply current to heating coil 32, instrument 35 indicating the flow of current. The circuit through thermostat 36 is normally open when the engine is cold. Valves 16, 27 and 30 are then adjusted and the plunger pump 26 is actuated to spray fuel onto the heating coil 32 where the fuel is ignited. The air for supporting combustion enters through inlet 23 and the products of combustion are exhausted through outlet 24 which is preferably larger in diameter than the inlet. The burning fuel heats the intake pipe and when the temperature of the latter reaches a predetermined point, depending upon the setting of 50 the thermostat 36, the latter is automatically

operated to short-circuit coil 32, and the resulting movement of the pointer of indicator 35 informs the operator that the intake pipe has been brought to the desired temperature for starting. Switch 33 may then be opened 70 and the starter (not shown) actuated to crank the engine. As the cold mixture of air and fuel passes through the heated section of the intake pipe said mixture is properly volatilized and the engine is easily started. 75

In Fig. 2 is shown another embodiment of the invention, wherein the fuel is sprayed into an annular chamber through a coil pipe 39 which is positioned in the lower part of the chamber surrounding intake pipe 14, suitable openings 40 being provided in the upper portion of pipe 37 for this purpose. A spark plug 41 is secured to the jacket 22 in a position to ignite the fuel issuing from openings 40 in pipe 39, current for said plug being provided by magneto or other suitable means (not shown) through leads 42. A plan view of the coil pipe and spark plug of Fig. 2 is shown in Fig. 3.

In Fig. 4 there is shown another embodiment of the invention wherein the jacket 43 which surrounds the intake pipe is substantially spherical in shape, and that portion of the intake pipe within the jacket is provided with fins 44 to more efficiently carry out the 90 heating action.

In Figs. 5 and 6 there is shown one type of thermostat which may be employed in accordance with the present invention. As illustrated, the device comprises a curved thermostatic element 45, which closely surrounds intake pipe 14 and is secured to a casing 46, which surrounds said intake pipe, the connection between the element 45 and casing 46 being shown at 47 with the thermostatic element insulated from the casing in any suitable manner. The free end of element 45 terminates closely adjacent a terminal 48 that extends through the wall of casing 46. The air gap between terminal 48 and element 45 100 may be adjusted, if desired, as by means of a threaded member 49 which is mounted in the wall of casing 46 and is adapted to engage the thermostatic element 45 intermediate its ends. The increase in temperature of the intake pipe which is transmitted to the thermostatic element 45 causes the latter to expand into engagement with the contact 48, whereupon the heating coil 32 is short-circuited and the indicating device is actuated to inform the operator that the desired temperature has been reached. 110

In Fig. 7 the novel preheater of the present invention is shown applied to an intake pipe 50 which is also fitted with a heater 51 that employs the gases of combustion of the engine to heat the intake while the engine is running, the exhaust manifold of the engine being diagrammatically shown at 52.

In Fig. 8 there is shown another embodi-

ment of the present invention wherein the air for supporting combustion within the jacket 53 of the preheater is introduced through an annular opening 54 which surrounds the intake pipe 14 closely adjacent the bottom of the preheater chamber. The air inlet member 55 extends upwardly beyond the bottom of the jacket 53 as at 56 to provide the necessary receptacle for holding the fuel introduced through nozzle member 28.

In Fig. 9 there is illustrated still another embodiment of the present invention wherein a heating coil 57, which is substantially vertically disposed within the jacket 58, is provided for igniting the fuel shown at 59. By this arrangement the ignition of the fuel proceeds from the upper surface thereof, the coil insuring that all fuel introduced into the preheater chamber will be burned.

It will be understood that the jacket for forming the annular chamber around the intake pipe may assume various shapes and forms and need not be made integrally with the intake pipe as illustrated. By making said jacket in readily attachable and removable sections the installation on engines now in use may be facilitated. It will be readily understood by those skilled in the art that thermostatic devices other than the one illustrated may be employed to indicate to the operator when the temperature of the intake pipe has been brought to the desired point.

The use of the apparatus greatly facilitates the starting of cold engines and overcomes the objectionable features pointed out above that have been present in devices of this character heretofore employed. The fuel drawn into the engine cylinders is not weakened by burned gases from the preheater and the latter, if desired, may be conducted by or through the lubricating oil tank 12 as shown in Fig. 1 to raise the temperature of the oil therein. Various changes may be made in the details of construction and arrangement of the parts and reference will therefore be had to the appended claims for the definition of the limits of the invention.

What is claimed is:

1. A device for heating the intake pipe of an internal combustion engine, prior to and after the starting of the engine, including a jacket surrounding a portion of the intake pipe and forming with the latter two annular chambers, means for introducing fuel into one of said chambers and for igniting said fuel therein, means operatively associated with said igniting means for indicating when the intake pipe has been raised to a predetermined temperature, and means for conducting exhaust gases from the engine through the other of said chambers.

2. A device for heating the intake pipe of an internal combustion engine, comprising a jacket surrounding a portion of said pipe and forming therewith a pair of annular

chambers, means for introducing liquid fuel into one of said chambers, including a nozzle and manually operable means for forcing fuel through said nozzle, means for igniting the fuel introduced into said chamber, means for conducting exhaust gases from the engine through the other of said chambers, and means including a thermostatic element indicating when the intake pipe has been heated to a predetermined temperature, said last named means also being adapted to automatically cease the operation of said igniting means when said predetermined temperature is reached.

In testimony whereof I have signed this specification.

JAMES M. SHOEMAKER.
